III-3-

III-4-

FIG. 1 is a right side elevational view of a lift truck embodying our new design.

FIG. 2 is a left side elevational view thereof.

FIG. 3 is a front elevational view thereof.

FIG. 4 is a rear elevational view thereof.

FIG. 5 is a top plan view thereof to an enlarged scale. The crisscross pattern shown in FIG. 5 is understood to be continuous throughout the areas defined, and is representative of a roughened or non-slip surface.

We claim:

The ornamental design for a lift truck, substantially as shown and described.
